ATTORNEY

UNITED STATES PATENT OFFICE.

RICHARD BAER, OF NEW YORK, N. Y.

LOCKING DEVICE.

Application filed March 24, 1921. Serial No. 455,013.

To all whom it may concern:

Be it known that I, RICHARD BAER, a citizen of Czechoslovakia, and resident of the borough of Manhattan, in the city, 5 county, and State of New York, have invented certain new and useful Improvements in Locking Devices, of which the following is a specification.

This invention relates to locking devices, 10 and has for its object to provide an improved locking device which will be substantially safe and not openable excepting by one who has an authorized key therefor. Generally speaking, the invention relates to 15 combination locks, but different from the usual run of combination locks, in that the mechanism is so arranged as to be very simple in manufacture, convenient in installation and secure in operation.

20 The invention will be more fully described in the following description and finally pointed out in the appended claims.

In the accompanying drawings:

Figure 1 is a view of a door having my 25 improved locking device attached thereto, the said door and jamb being shown only in part;

Figure 2 is a horizontal section taken on the line 2—2 of Figure 1;

30 Figure 3 is an enlarged view of the locking device which is shown in Figure 2;

Figure 4 is a vertical section taken on the line 4—4 of Figure 3;

35 Figure 5 is a vertical section taken on the line 5—5 of Figure 3; and

Figure 6 is a vertical section taken on the line 4—4 of Figure 3 but with the several members in different positions in respect to 40 each other depending upon the combination of the key inserted therein; and

Figure 7 is a perspective view of one embodiment of a key; and

Figure 8 is a perspective view of another embodiment of the key in which the key is 45 in folded position.

Similar characters of reference indicate corresponding parts throughout the various views.

Referring to the drawings and more particularly to Figures 1 and 2, the usual door 50 is therein shown suitably hinged at 11 to one jamb 12 and abutting against the other jamb 13. Secured to the jamb 13 is one portion of the lock indicated in general by 55 15 in Figures 1 and 2 and secured to a position on the door 10. Opposite to the part

15 is the other part of the lock indicated by 16 in Figures 1 and 2. The part 15 is composed of an embracing shell 20 having therein a movable latching member 21 adapted to be moved by means of a handle 22 secured by screw threads to the latching member 21 and protruding outwardly therefrom. The enclosing shell or casing 20 has a slot 23 acting as a guide slot in which the handle 22 may move to and fro against the action of the spring 24 which is held at one end on a protruding rod 24 and which seats in a cavity 26 of the latching member. The latching member itself has a conical or beveled surface 27 and a square shaped corner surface 28. This casing 20 may be applied to the door jamb 13 by suitable screws or other fastening means as indicated by 29 in Figure 1.

The other part of the locking device consists of a casing 30 within which is arranged a plurality of guide channels running throughout the length of the casing and indicated by 31. Within these guide slots 31 80 are arranged helical springs 32, one spring for each slot or channel. Within the guide channels are also arranged a plurality of members each in the shape of a cube indicated by 33.

In the embodiment shown in Figure 4 for instance there are shown eight (8) cubes. The cubes are so arranged as to be next to each other and to be movable within the guide channel or guide slots 31 and also 90 movable in the circular passage indicated by 35 of the guide slot 31. Thus by moving the series of cubes within the guide slots or guide channels the springs 32 will become compressed and when pressure is 95 released on the outermost cube the spring will expand and force the series of cubes back to the original position as shown in Figures 3 and 4. Each channel has a key slot 38, as shown in Figures 3 and 4. This 100 is adapted to receive a beard of the key and to guide the same. Each slot 38 permits the ready entrance of each beard 39 of the key 40. The remaining cubes are utilized to work out by a series of permutations, a 105 combination action. Thus, the eight cubes in each guide slot and the four guide slots, provide 36 cubes, and hence a large number of combinations could be worked out as will readily appear.

110 In the combination shown in the embodiment of the drawing, the second cube of the

uppermost channel, as seen in Figure 4, is provided with a slot or recess indicated by 41. In the second channel of the embodiment of Figure 4, the sixth cube is provided with a slot or recess 42. In the third channel the eighth cube is provided with a slot or recess 43, and in the fourth channel the fourth cube is provided with a slot or recess 44. It is only when these four recesses or slots 41 to 44 are brought together in a vertical line that it is possible to bring about the alignment of the slots so as to enable the lock to be opened. When these four cubes are brought into alignment then the slots or recesses therein permit a spring actuated member 50 to be moved and this then permits the stems 51 thereof, as shown in Figures 3 and 5, to enter within the recesses or slots 41 to 44. The member 50 is connected with a handle or key 52 at the outside of the door and this handle can only be operated so as to move the member 50 and the stems 51 within the cubes as before described, when the recessed cubes are brought into alignment with each other. In this condition, these stems 51 will then enter the openings 41 to 44 and this then will permit the complete movement of the member 50 and permit also thereby the disengagement of the protruding latching member 55 from the portion 28 of the latching member 21. The door may then be opened.

It will thus be clearly seen that the locking device can only be operated as to be opened when an authorized key 40 is used. Namely, a key must be provided which has its beards of such length that they will force the recessed cubes into that position as to cause the particular recessed cubes to be brought into alignment, at which time only the stems 51 can enter into the slots or recesses and thereby permit the handle 52 to be operated and the latching member 55 withdrawn from the latching member 21. Should any of the beards be of a different size than such as to compel the cubes to be moved to the proper distance inwardly of the guide channels the combination will not result.

In Figure 8, I have shown a key 70 in which the beards are hinged on their base and which beards 71 may be folded downwardly so as to make a very compact key that can be readily carried in the pocket.

In Figure 5, the handle 52 has a stem portion 58 projecting through the door so as to engage with the latching member 50 by means of the guide 59 and this handle may also be shaped in the form of a key that may be replaced or removed. In the preferable embodiment, I make the handle 52 detachable.

The guide slots 38 of the guide channels as shown in Figure 3 may be provided with

a cover 62 suitably hinged at 63 to the casing or holding portions 64 by means of which the guide channel portion may be suitably secured to the door by screws 65 or other fastening means. The guide channels are preferably formed within a casing 66 as shown in Figure 4 which is provided with three partitions in the embodiment shown, which partitions are indicated by 67, 68 and 69. The casing 66 may also be provided with an extension 70^a which may be suitably secured to the door 10.

One advantage of my improved locking device is that it is very simple in its manufacture. The provision of a casing may be readily carried out and this casing may be readily provided with partitions which may be separate from the casing and readily inserted into the casing itself. This can be done by castings or machine work. The cubes referred to may be readily made of metal and lend themselves admirably in their guidance in the channel. They also lend themselves readily to a change in the combination should it be desired to change this combination, the cubes as shown in Figure 4 can be transposed so as to form any combination or the slots or recesses therein can be closed up by means of a suitable metal filling and slots or recesses can be supplied in other cubes. This will then require a key of a different shape to operate the cubes and bring them in the position so that the openings are in alignment with each other, so as to permit the stems 51 to enter therein on the operation of the handle or key 52.

One of the important uses of my invention is the application of the locking device to doors, but another equally important use thereof is in connection with automobiles, so as to provide a secure lock for automobiles which can only be operated and opened by means of a definite key of a definite configuration. The operation of the entire device is most simple: The key 40 or 70 is inserted and the cubes are then moved until the recessed cubes are in alignment. Then the key or handle 52 is operated and the stems 51 enter the recesses of the cubes. Thereby the locking disengagement results. The stems 51 cannot be operated to disengage the locking members until a passage for the stems 51 is provided. And this can only be provided by a key of proper shape.

I have described several embodiments of my invention, but changes may be made therein without departing from the spirit of my invention, as defined in the annexed claims.

I claim:

1. An improved locking device comprising a casing having a series of guiding channels, springs therein, cubical members in the channels urged to an initial position by the

springs, certain of said cubical members having recesses, means engageable with the cubical members to urge them from the initial position against the influence of said

5 springs to a position of alinement of the recessed members, and a latching member having stems adapted to enter the alined recesses of said cubical members.

2. An improved locking device consisting 10 of a casing having a plurality of slots therein, helical springs within each slot, a plurality of cubical members guided in each slot, a latching member, stems on the latching member adapted to enter openings in 15 the cubical members when said openings are in alignment with each other, and a key having projections of different lengths adapted to enter the casing and move the series of cubical members until the apertured mem-

bers thereof are in alignment with each other 20 when the latching member may enter the slots or recesses of the cubical members whereupon the door may be opened.

3. A lock comprising a casing, a series of rows of permutation members in the casing 25 normally held in an initial position, certain of said permutation members having recesses therein, a latch having pins adapted to engage in the recesses of said permutation members when the recessed members are 30 alined, and a key for shifting said rows of permutation members in the casing to effect alinement of the recessed members.

In testimony that I claim the foregoing as my invention, I have signed my name here- 35 under.

RICHARD BAER.
